UNITED STATES PATENT OFFICE.

DAVID LIPPY AND JACOB B. ROUSH, OF MANSFIELD, OHIO.

TRACTION-ENGINE.

SPECIFICATION forming part of Letters Patent No. 230,297, dated July 20, 1880.

Application filed April 3, 1880. (No model.)

To all whom it may concern:

Be it known that we, DAVID LIPPY and JACOB B. ROUSH, of Mansfield, in the county of Richland and State of Ohio, have invented 5 a new and useful Improvement in Traction-Engines, of which the following is a specification, reference being had to the accompanying drawings.

The invention relates to an improvement in 10 traction-engines; and it consists in the devices hereinafter described, and particularly pointed out in the claims.

The object of the invention is to provide an 15 efficient means for causing the boiler of the engine to assume a horizontal position whether its carriage is passing up or down hill or traveling upon a level plane. The devices regulating the position of the boiler are actuated by the engine-shaft, and are under the full 20 control of the attendant.

Referring to the accompanying drawings, Figure 1 is a side view of an engine containing an embodiment of the elements of the invention. Fig. 2 is a top view of same. Fig. 3 25 is a section showing the gearing within the boiler, with a detached side view of the pinion *k* and rack *m*.

A indicates the boiler, having the usual firebox at its rear end, and mounted upon the 30 wheels *B*, those at the rear being rigidly secured and the forward ones being pivotally mounted, so as to permit the engine to be readily turned when desired.

D represents the engine-shaft, which drives 35 the devices constituting our invention. This shaft is, in the present instance, mounted transversely over the front part of the boiler *A*, and has upon one end the clutch-box *a*, one half, *b*, being loosely secured and provided with 40 a sheave-wheel, *d*, while the other half, *e*, is mounted upon a feather and may be controlled as to its movement by the lever *f*, which affords a means whereby the attendant may cut off the action of the engine-shaft from the remaining mechanism or transmit said action to 45 the said mechanism, as may be desired.

Forward of the end of the shaft *D*, and a little to one side of the clutch-box *a*, is secured upon the stand *E* the pulley-wheel *h*, and just 50 forward of the stand *E* is secured another stand, *H*, in which is mounted the vertical

shaft *I*. Upon the lower end of the shaft *I* is secured a worm, *i*, which meshes with the pinion *j*, mounted upon the end of the shaft *k*, which shaft passes through the front end of the boiler at about its horizontal transverse center, and is supplied centrally within the same with the pinion *l*. This pinion meshes with the rack *m*, secured to or made a part of the vertical rod *n*, which extends upward within the boiler, and has its lower end connected with the axle of the front wheels, *B*, by a ball-and-socket joint, or otherwise. When the shaft *k* is revolved the pinion *l* either rides up or down the rack *m*, according to the direction 65 in which it is turned, and in this way either elevates or depresses the front end of the boiler.

Upon the upper end of the shaft *I* are mounted, so as to turn thereon, the two 70 sheave-wheels *p*, which are separated a suitable distance, and are supplied upon their sides facing each other with the clutches *s*, one being a right and the other a left clutch. Between these clutches *s* is mounted, upon 75 the shaft *I*, the double clutch-box *t*, the teeth upon the upper side of which are adapted to engage the upper clutch *s* and the teeth upon the lower side the lower clutch *s*. The clutch *t* is capable of being moved either toward or from 80 either clutch *s*, and is mounted upon a feather connected with the shaft *I*. Thus when the clutch is revolved the shaft will be operated also in the same direction. If the clutch *t* is engaged with the upper clutch *s*, it will be 85 revolved with the same, and the shaft *I* will have the same movement. When the clutch *t* is operated by the lower clutch *s* it will revolve in the reverse direction and communicate a like movement to the shaft *I*. The 90 clutch *t* is moved either toward or from either clutch *s* by the angle-arm *u* and weight or counterpoise *w*, according as the boiler is inclined upward or downward. The angle-arm *u* is pivotally secured in front of the shaft *I*, 95 and has one of its arms loosely connected with the clutch *t*, the other arm having attached thereto the weight *w*. When the boiler is inclined upward the weight *w*, in seeking a perpendicular position, forces the clutch *t* up 100 against the upper clutch *s*, and when the boiler is inclined downward the weight, again

seeking a level, carries, through the angle-arm *u*, the clutch *t* down in contact with the lower clutch *s*.

An endless chain, *x*, is placed on the wheel *h* and the wheels *d p* for the purpose of imparting motion to the different elements of the machine.

When the engine-shaft *D* is in operation the clutches and chain may be held idle by simply disengaging the halves of the clutch-box *a*, or its movement may be communicated to the said device by connecting the said halves.

When the halves of the clutch-box *a* are connected and the carriage is traveling on a level plane the chain and sheaves are in operation and the clutch *t* rests stationary midway between the clutches *s*, the shaft *I* being also idle. But in case the carriage should start up an incline, the counterpoise *w*, seeking a perpendicular position, will force the clutch *t* in contact with the upper clutch *s*. This, as hereinbefore set forth, will operate the shaft *I* to revolve with the said clutch, which movement will cause the shaft *k* to revolve and the pinion *l* to ride down the rack *m*, gradually lowering the front end of the boiler to a level with its rear end. In traveling down an incline the clutch *t* meshes with the lower clutch *s* and operates the shaft *I* to revolve in a reverse direction, causing the pinion *l* to ride up the rack *m*, and thus gradually elevating the front end of the boiler to the same plane with its rear end.

In the ball-and-socket joint connecting the front axle, *a'*, with the rod *n* the ball *b'* is formed or secured upon the end of the rod *n*, and is smaller than the socket *d'*, in order that when the front end of the boiler is at its lowest extremity the rod *n* may raise at least the length of one cog, and the rack *m* and pinion *l* be thereby prevented from breaking at any sudden movement of the engine.

To the axle of the front wheels, *B*, is secured one end of a rod, *m'*, the other end of same being pivotally attached to the fire-box or rear of the boiler. The purpose of the rod *m'* is to brace and secure the proper operation of the front axle and rod *n*. The rear end of the rod *m'*, being pivotally secured, permits the front axle to be elevated or depressed without exerting a strain on the rod.

What I claim as my invention, and desire to secure by Letters Patent, is—

1. The clutch-box *a* and chain *x*, in combination with the clutches *s* and *t*, the shaft *I*, shaft *k*, and rod *n*, connected by intermediate gearing, substantially as specified.

2. The clutches *s* and *t* and chain *x*, in combination with the shaft *I* and counterpoise *w*, substantially as and for the purpose set forth.

3. The clutch-box *a*, sheave *h*, clutches *s t*, and chain *x*, in combination with the shaft *I*, counterpoise *w*, pinion *j*, shaft *k*, pinion *l*, and rack *m*, substantially as set forth.

4. The rod *n*, having a rack, *m*, upon its face, and connected with the axle of the front wheels, *B*, by a ball-and-socket joint, the ball being sufficiently smaller than the socket to allow the rod a vertical movement equal to the length of one of the teeth on the rack *m*, in combination with the pinion *l*, shaft *k*, pinion *j*, worm *i*, shaft *I*, and suitable gearing for giving the said shaft *I* either a right or left movement, substantially as set forth.

In testimony that we claim the foregoing improvement in traction-engines, as above described, we have hereunto set our hands this 17th day of March, 1880.

DAVID LIPPY,
JACOB B. ROUSH.
